UNITED STATES PATENT OFFICE.

WALLACE S. WARNOCK, OF CHICAGO, ILLINOIS.

DEVICE FOR REGULATING THE TEMPERATURE OF INK-ROLLERS.

1,369,507.

Specification of Letters Patent. Patented Feb. 22, 1921.

Application filed September 18, 1920. Serial No. 411,348.

To all whom it may concern:

Be it known that I, WALLACE S. WARNOCK, a citizen of the United States, residing at 7726 Eastlake Terrace, Chicago, in the county of Cook and State of Illinois, have invented a new and useful Improvement in Devices for Regulating the Temperature of Ink-Rollers, of which the following is a specification.

10 This invention relates particularly to means for regulating the temperature of transfer rollers of the inking mechanism of a press.

15 The primary object is to provide means for maintaining the rollers at a suitable temperature to keep the ink in the best condition for use and preserve the composition rollers.

20 The invention is illustrated in its preferred embodiment in the accompanying drawings in which—

Figure 1 represents a broken side elevational view of the inking mechanism of a press, embodying my invention; Fig. 2, a 25 similar view taken from the opposite side of the machine; Fig. 3, a broken plan view of the same; Fig. 4, a broken view showing the modification of the means for admitting hot and cold water to the rollers; Fig. 5, a 30 vertical sectional view taken as indicated at line 5 of Fig. 1; Fig. 6, a sectional detailed view taken as indicated at line 6 of Fig. 5, this view showing the intake end of one of the rollers; Fig. 7, a sectional view taken 35 as indicated at line 7 of Fig. 6; and Fig. 8, a sectional view taken as indicated at line 8 of Fig. 5, this view showing the outlet end of one of the rollers.

40 In the construction illustrated, A represents the bed which carries the inking mechanism of a press, and in which is mounted a longitudinally reciprocable ink-plate A'; B, an oscillating transfer roller which receives ink from a pair of rollers B' which 45 take their supply from the plate A', the roller B serving to transfer the ink to a roller B², which aids in distributing the ink on the roller B; C, a transfer roller which receives ink from a pair of rollers C' which 50 take their supply from the plate A', the roller C serving to transfer the ink to a roller C², which aids in distributing the ink on the roller C; D, means for admitting water at a given temperature to the interiors 55 of the transfer rollers B and C; and E,

means for educting water from the rollers B and C.

It is common, in this type of machine, to apply ink to the reciprocating plate A' by means of transfer rollers (not shown) which 60 take the ink from the fount and distribute it on the plate A'. The ink is carried by the plate A' beneath the pair of rollers B' and the pair of rollers C', is taken up by these rollers and distributed over the longitudinally reciprocating rollers B and C, which act as distributing rollers, and finally 65 it is taken from the rollers B' and C' and transferred to the form (not shown), which reciprocates in the same plane as the ink-plate A'.

The pair of rollers B' and the pair of rollers C' are non-oscillating, these rollers being supported in bearings 1 with which the bedded machine is provided. The rollers B and C are supported in bearings 2 at a higher plane; and the rollers B² and C² are supported by bearings 3 at a still higher 70 plane.

The rollers B and C are preferably hollow steel rollers and are provided with long hollow shafts 4 which are equipped near one end with collars 5. These collars are engaged by an oscillating lever 6, which serves in the usual manner to oscillate the 75 rollers B and C longitudinally. The other rollers of each group may be composition rollers. The shafts of the rollers are connected by pinions 7 in the usual manner; and by suitable gearing (not shown) the 80 rollers may be turned in one direction and in the other direction, as is common in the art.

The means D for admitting water of desired temperature to the rollers B and C comprises an inlet pipe 8 which may be regarded as a hot water pipe, an inlet pipe 9 which may be regarded as a cold water pipe, these pipes serving to deliver water through a single connection 10 to a fitting 11 which serves as a mixing chamber, in which fitting 100 is mounted a thermometer 12, a pipe 13 leading from the fitting 11 and connecting, through a flexible hose 14 with the intake end of the roller B; and another pipe 15 leading from the fitting 11 in the opposite 105 direction and connecting, through a flexible hose 16, with the intake end of the roller C.

The fitting or connection 10 comprises a valve casing fitted with a valve controlled by a thermostat 17, of any suitable type. 110

Such thermostat may be purchased on the market and applied in the manner understood by those skilled in the art, the device serving to regulate the admission to the rollers B and C, according to the temperature of the water. It should be added that the valves 8^a and 9^a may be so regulated as to admit to the mixing chamber 10 water of somewhat higher temperature than is desired for passage through the rollers; and when the temperature in the fitting 11 falls below a predetermined degree, the thermostat will operate to admit warmer water to the fitting 11 and thence through the pipes 13 and 15 to the rollers B and C.

The pipes 8 and 9 are equipped with end valves 8^a and 9^a, by means of which the admission of water may be regulated to give the temperature in the mixing chamber which is desired for admission to the rolls. If desired, instead of employing the fitting 10 and an automatic valve for regulating the flow of water therethrough, one may employ a plane by connection 10^a in the manner shown in Fig. 4. In such case, the admission of the water to secure a mixture of the desired temperature may be controlled wholly by means of the valves 8^a and 9^a shown in Fig. 1.

30 The water outlet device E comprises a flexible hose 18 connected with the outlet end of the roller B; a flexible hose 19 connected with the outlet end of the roller C; branch pipes 18^a and 19^a connected with the hose mentioned and communicating through a common fitting 20 with a common outlet pipe 21 which is equipped with a valve 21^a.

The manner of connecting the hose with the inlet and outlet ends of the rollers will be understood from Figs. 1 and 2 and 6 to 8 inclusive. Thus, at the inlet end of the roller B, the hose 14 is attached to a nipple 22 which projects radially from a metal bulb 23 which is secured to the outer end of a short tube, or small pipe 24, which projects from and is journaled in a stuffing-box 25 which is secured to the inlet end of the shaft 4. The details will appear from Figs. 5, 6 and 7. The stuffing-box rotates about the tube 24, which tube is provided at its inner end with a flange or collar 24^a. The stuffing-box 25 comprises a cup 25^a having a taper threaded shank 25^b which screws into the end of the tubular shaft 4; a gland 25^c which encircles the tube 24 and screws into the outer end of the cup 25^a; a lock-nut 25^d applied to the gland; a fiber washer 25^e interposed between the gland 25^c and the collar 24^a; a fiber washer 25^f on the inner end of the tube 24 and interposed between the collar 24^a and the bottom of the cup 25^a; and a felt washer 25^g encircling the fiber washer 25^f. Oil ducts 25^b and 25ⁱ are provided in the bearing. The bulb 23 is equipped with 65 radial studs 23^a, any one of which may serve

as a pivotal connection for one end of an extensible link 26, which comprises two telescoping sections 26^a and 26^b, as shown in Fig. 1. The intake connection for the hose 16 which communicates with the roller C is 70 the same as that just described, and the parts are designated by the same reference characters. The other end of the extensible link 26 is pivotally connected with one of the studs 23^a of the bulb 23 which forms a part 75 of the connection with the shaft of the roller C. The purpose of providing a number of pivotal studs 23^a is for convenience in applying the extensible link 26, regardless of the angular position of the tube 24, which may 80 be turned to any desired position for conveniently attaching the hose to the nipple 22. As shown in Fig. 6, the nipple 22 has its outer end threaded interiorly and fitted with a reducing nipple 22^a, which has a smaller 85 bore. This feature is employed for the reason that it is desired to provide the rollers with smaller induction passages than are the eduction passages, thus avoiding any back pressure which might tend to cause leakage 90 at the stuffing-boxes provided at the ends of the shafts of the rollers.

At the eduction ends of the rollers B and C are provided connections for the hose 18 and 19 which are similar in construction to the construction already described, and the parts are therefore indicated by the same reference characters. In this case however, the reducing nipple 22^a with which the nipple 22 is provided, has a larger bore than has the corresponding nipple at the inlet end. This will be seen by observation of Figs. 6 and 8. Also, the shank 25^b of the stuffing-box 25^a, instead of being screwed directly into the end of the shaft 4 is screwed into 100 an enlarged connecting sleeve 27, as shown in Fig. 5.

From the description given, it will be understood that the ink distributing rollers B and C have a movement of oscillation longitudinally, as well as a movement of rotation and reverse rotation, as is usual in this type of mechanism. Also, it will be understood from Fig. 3 that the rollers B and C move simultaneously in opposite directions 115 in making their longitudinal oscillations, hence the necessity of employing the extensible connecting links 26. These links serve to maintain the non-rotating tubes 24 in a given angular position, and prevent the 120 tubes from rotating with the rollers. In the operation of the apparatus, hot water may be admitted through the inlet pipe 8, for example, and cold water may be admitted through the inlet pipe 9, the mixing being 125 effected during the passage of the two streams of water after they unite and while they are being conducted in the fitting 11, where the resultant temperature of the water is registered by the thermometer. Thus, 130

water of the proper temperature to maintain the ink in the best condition for use is admitted to the metal rollers B and C, and this temperature is communicated to the other 5 rollers of the nests of rollers. In case the printing press is operating in a hot climate or during very hot weather in a temperate climate, cooling water may be introduced in the system, as may be necessary to maintain 10 the ink of the desired consistency.

It may be added that it is a most important object of the invention to maintain the composition rollers of the inking mechanism at a proper temperature to prevent the 15 rollers from being injured in the operation of the mechanism. It may be explained that in the operation of such inking mechanism, the friction developed is such as to cause heating and thus injure the stability of the 20 composition of which the inking rollers are ordinarily formed. In other words, especially in hot weather, or in fast-running presses in ordinary temperatures, there is danger of the composition of the rollers becoming 25 excessively heated and melted. This danger is obviated by the present invention, and the rollers may be kept at the desired temperature, while any desired working temperature is maintained in the room in which 30 the press is situated. In cold weather, or in the operation of starting a press at any time, it is desirable to be able to heat the rollers for the purpose of making them sufficiently soft or "tacky" to properly distribute the ink. 35 While the inking rollers are shown associated with a reciprocating inking-plate of a flat-bed press, it will be understood that the ink may be delivered to the inking rollers in any suitable manner, and that the ink 40 may be transferred by the rollers to any form of printing member, as, for instance, to the form cylinder of the rotary press.

The improved apparatus meets a long felt want in the art, and has proven, in practical 45 operation, thoroughly effective for the purpose.

The foregoing detailed description has been given for clearness of understanding only and no unnecessary limitations should 50 be understood therefrom, but the appended claims should be construed as broadly as permissible in view of the prior art.

What I regard as new, and desire to secure by Letters Patent, is:

55 1. The combination with a hollow inking roller provided with a tubular shaft, of means for mixing hot and cold water and admitting the mixed water to the roller through one end of the shaft, and means for 60 educating the water from the other end of the shaft.

2. In apparatus of the character set forth, the combination with a hollow inking roller provided with a tubular shaft, of means for 65 mixing hot and cold water and indicating

the temperature of the mixture, means for admitting the mixed water to one end of said shaft, and means for educting water from the other end of said shaft.

3. In apparatus of the character set forth, 70 the combination of a pair of rotating, longitudinally oscillating hollow inking rollers provided with tubular shafts, a source of water supply, means for conducting the water to the vicinity of the admission ends of 75 said shafts, stuffing-boxes applied to the ends of said shafts, said stuffing-boxes having tubular members journaled therein, the outer ends of said tubular members being connected with the water conducting means, 80 an extensible link having radial pivotal connection with the outer ends of said tubular members, and means for educting water from the discharge ends of said tubular shafts. 85

4. In apparatus of the character set forth, 90 the combination of a pair of rotating, longitudinally oscillating hollow inking rollers provided with tubular shafts, stuffing-boxes applied to the admission ends of said shafts, 95 tubular members journaled in said stuffing-boxes and equipped at their outer ends with radial studs, an extensible link pivotally connected at its end with said radial studs, hose connected with said tubular members, a water mixing device communicating with said hose, hot and cold water devices communicating with said water mixing device and equipped with valves, and means for educting the water from the discharge ends 100 of said tubular shafts. 105

5. In apparatus of the character set forth, 110 the combination of a pair of rotating, longitudinally oscillating hollow inking rollers provided with tubular shafts equipped with stuffing-boxes, tubular members projecting from said stuffing-boxes and equipped with radial studs, extensible links having their ends pivotally connected with said radial studs, means for admitting fluid at regulated 115 temperature to the tubular members at one end of the inking rollers, and means for conducting fluid from the tubular members at the other end of the inking rollers. 120

6. In apparatus of the character set forth, 125 the combination with a pair of rotating, longitudinally reciprocating hollow inking rollers equipped with tubular shafts, of temperature regulating means comprising means for educating water from the tubular shafts at one end, and means for introducing water into said tubular shafts at the other end, comprising stuffing-boxes secured to the shafts at their admission ends, tubes projecting from said stuffing-boxes and equipped with bulbs provided with radial studs and radial nipples, an extensible link having its ends pivotally connected with said radial studs, hose connected with said nipples, branch pipes connected with said hose and 130

connected also with a fitting, to said pipes, valved hot water and cold water admission pipes connected with a common fitting, and a union connecting said first named fitting 5 with said second named fitting.

7. In apparatus of the character set forth, the combination with a pair of rotating, longitudinally reciprocating hollow inking rollers, of means for admitting water thereto 10 at regulated temperature, comprising a mixing device, conduits leading from the mixing device and communicating with the interiors of said rollers at one end thereof, hot and cold water admission pipes communicating with said mixing device, and an automatic valve regulating the passage of water 15 through the mixing device.

8. In apparatus of the character set forth, the combination with a pair of rotating, 20 longitudinally reciprocating hollow inking rollers, of means for admitting water thereto at regulated temperature, comprising a mixing device, conduits leading from the mixing device and communicating with the interiors of said rollers at one end thereof, hot and cold water admission pipes communicating with said mixing device, an automatic valve regulating the passage of water 25 through the mixing device, and hand valves controlling the passage of water through the hot and cold water admission pipes.

9. In apparatus of the character set forth, the combination with a rotating, longitudinally reciprocating hollow inking roller 30 equipped with a hollow shaft, stuffing-box secured to one end of said shaft, a tubular

member journaled in said stuffing-box equipped at its outer end with a bulb, a nipple carried by said bulb and adapted for connection with a hose and a radial stud 40 carried by said bulb and adapted to serve as a pivotal connection for a connecting rod.

10. The combination of a reciprocating inking plate, a pair of non-oscillating inking rollers contacting with said plate, a rotating, longitudinally oscillating distributing roller contacting with said first named rollers, a non-oscillating inking roller contacting with said distributing roller and 45 adapted to convey the ink to the form, means for admitting water of regulated temperature to one end of the distributing roller, and means for educting the water from the other end of the distributing roller. 50

11. The combination of a reciprocating inking plate, a pair of non-oscillating inking rollers contacting with said plate, a rotating, longitudinally oscillating distributing roller contacting with said first 55 named rollers, a non-oscillating inking roller contacting with said distributing roller and adapted to convey the ink to the form, means for admitting water of regulated temperature to one end of the distributing roller, and means for educting the water from the other end of the distributing roller, the eduction passage from the distributing roller being larger than the induction passage to said distributing roller. 60

WALLACE S. WARNOCK
